DESIGN FOR A SMOKER'S ASH TRAY

Thomas Richard Lulham, London, England

Application September 10, 1934, Serial No. 53,248
In Great Britain May 11, 1934

Term of patent 14 years

To all whom it may concern:

Be it known that I, THOMAS RICHARD LULHAM, a British subject, residing at 67 Highbury Hill, London, N. 5, England, have invented a new, original, and ornamental Design for a Smoker's Ash Tray, of which the following is a specification, reference being had to the accompanying drawing, forming a part thereof.

The drawing consists of a perspective view of the smoker's ash tray showing my new design.

I claim:

The ornamental design for a smoker's ash tray as shown.

THOMAS RICHARD LULHAM.
